9 Claims

ABSTRACT OF THE DISCLOSURE

O-pyrazolopyrimidine - (thiono) - phosphoric - (phosphonic or phosphinic)-acid esters or ester-amides of the general formula

in which

R₁ is alkoxy or alkyl with 1 to 6 carbon atoms,
R₂ is alkyl or alkoxy with 1 to 6 carbon atoms, or phenyl, or a monoalkylamino or dialkylamino group with up to 6 carbon atoms per alkyl moiety,
R₃ is hydrogen or halogen, and
X is oxygen or sulfur,

which possess insecticidal, acaricidal and rodenticidal properties.

The present invention relates to and has for its objects the provision of particular new O-pyrazolopyrimidine-(thiono) - phosphoric - (phosphonic or phosphinic)-acid esters or ester amides, i.e. (thiono) phosphoric, phosphonic or phosphinic acid esters or ester amides of (optionally 3-halo-substituted)-2-hydroxy-pyrazolo[1,5-a]pyrimidine, which possess insecticidal, acaricidal and rodenticidal properties, active compositions in the form of mixtures of such compounds with solid and liquid dispersible carrier vehicles, and methods for producing such compounds and for using such compounds in a new way especially for combating pests, e.g. insects, acarids and rodents, with other and further objects becoming apparent from a study of the within specification and accompanying examples.

It is known from Belgian Patent Specification 676,802 and Netherlands Published Patent Application 6516907 that O-pyrazolopyrimidine - (thiono) - phosphoric-(phosphonic or phosphinic)-acid esters, for example O,O-diethyl - O - (5,7 - dimethylpyrazolo[1,5 - a]pyrimidin(2)yl)-thiono-phosphoric acid ester (Compound A) and O,O-diethyl-O-(3-chloro- (Compound B) or -3-bromo-5,7 - dimethylpyrazolo-[1,5 - a]pyrimidin(2)ylphosphoric acid ester (Compound C), display a pesticidal action, especially an insecticidal and acaricidal action.

The present invention provides O-pyrazolopyrimidine-(thiono) - phosphoric - (phosphonic or phosphinic)-acid esters or ester-amides of the general formula

in which

R₁ is alkoxy or alkyl with 1 to 6 carbon atoms,
R₂ is alkyl or alkoxy with 1 to 6 carbon atoms, or phenyl, or a monoalkylamino or dialkylamino group with up to 6 carbon atoms per alkyl moiety,
R₃ is hydrogen or halogen, and
X is oxygen or sulfur.

Surprisingly, the compounds of the invention show a considerably higher insecticidal and acaricidal action than the previously known compounds of analogous structure and the same type of action. The substances according to the invention thus represent a genuine enrichment of the art.

Preferably, R₁ is straight-chain or branched lower alkyl with 1 to 4 carbon atoms, such as methyl, ethyl, n- or isopropyl, n-, sec-, tert- or iso-butyl, or straight-chain or branched lower alkoxy with 1 to 4 carbon atoms, for example methoxy, ethoxy, n- or iso-propoxy or n-, sec-, tert- or iso-butoxy; R₂ is such lower alkyl or alkoxy, or phenyl, or mono-lower alkylamino or di-lower alkylamino with up to 4 carbon atoms in each alkyl moiety, such as a mono-methylamino, monoethylamino, mono - isopropylamino, mono-n-propylamino, mono - n - butylamino, mono-sec-butylamino, mono-iso-butylamino, mono-tert-butylamino, dimethylamino, di-ethylamino, di-n-propylamino, di-isopropylamino, di-n-butylamino, di-isobutylamino, di-tert-butylamino, di-sec-butylamino, methyl-isopropylamino or like radical; R₃ is hydrogen, chlorine or bromine.

As examples of (thiono)-phosphoric-(phosphonic or phosphinic)-acid esters or ester-amides of the formula (I) which can be used, the following may be mentioned individually: O,O-dimethyl-, O,O-diethyl-, O,O-di-n-propyl-, O,O-di-iso-propyl-, O,O-di-n-butyl-, O,O-di-iso-butyl-, O,O-di-sec-butyl-, O,O-di-tert-butyl-, O-methyl-O-ethyl-, O-methyl-O-n-propyl-, O-methyl-O-isopropyl-, O-methyl-O-n-butyl-, O-ethyl-O-n-propyl-, O-ethyl-O-isopropyl-, O-ethyl-O-n-butyl-, O-ethyl-O-tert-butyl-, O-n-propyl-O-n-butyl-, O-iso-propyl-O-n-butyl- or O-iso-propyl-O-tert-butylphosphoric acid ester and the corresponding thiono analogues, and also O-methyl-, O-ethyl-, O-n-propyl-, O-iso-propyl-, O-n-butyl-, O-sec-butyl-, O-isobutyl- and O-tert-butyl-methane-, -ethane-, -propane-, -butane- and -benzene-phosphonic acid ester as well as dimethane-, diethane-, di-n-propane-, di-iso-propane-, di-n-butane-, di-iso-butane-, di-sec-butane-, di-tert-butane-, methane-butane- and methane-benzene phosphinic acid-ester, also O,N-dimethyl-, O-methyl-N-ethyl-, O-methyl-N-n-propyl-, O-methyl-N-iso-propyl-, O-methyl-N-n-butyl-, O-methyl-N-sec-butyl-, O-methyl-N-iso-butyl-, O-methyl-N-tert-butyl-, O-ethyl-N-methyl-, O-ethyl-N-ethyl-, O-ethyl-N-n-propyl-, O-ethyl-N - n - iso - propyl-, O-ethyl-N-n-butyl-, O-ethyl-N-sec-butyl-, O - ethyl - N - iso - butyl-, O-ethyl-N-iso-butyl-, O-ethyl-N-tert-butyl-, O-n-propyl-N-methyl-, O-n-propyl-N-ethyl-, O,N-di-isopropyl-, O-iso-propyl - N - n - butyl-, O-iso-propyl-N-iso-butyl-, O-isopropyl-N-sec-butyl-, O-iso-propyl - N - tert-butyl-, O - n - butyl-N-methyl-, O-n-butyl-N-ethyl-, O-n-butyl-N-n-propyl-, O-n-butyl-N-iso-propyl-, O-n-butyl-N-iso-butyl-, O,N - di - n - butyl-, O-n-butyl-N-tert-butyl-, O-tert-butyl-N-methyl-, O-tert - butyl - N - ethyl-, O-tert-butyl-N-ethyl-, O-sec-butyl-N-ethyl-, O-sec-butyl-N-n-propyl-, O-sec-butyl-N-iso-propyl- or O-sec-butyl-N-n-butyl-phosphoric acid ester amide, as well as the corresponding dialkylamino ester amide and their thiono analogue esters of 2-hydroxy-pyrazolo[1,5-a]pyrimidine or its 3-chloro- or 3-bromo derivative.

The invention also provides a process for the production of an O-pyrazolopyrimidine-(thiono)-phosphoric-(phosphonic or phosphinic)-acid ester or ester-amide of the formula (I) in which a (thiono)-phosphoric-(phosphonic or phosphinic)-acid ester halide or ester-amide halide of the general formula

(II) 10

in which

R_1 , R_2 and X have the above-mentioned meanings, and Hal is halogen, preferably chlorine or bromine,

is reacted with a 2-hydroxypyrazolopyrimidine derivative of the general formula

(III)

in which

R_3 has the above-mentioned meaning,

in the presence of an acid acceptor or in the form of the corresponding alkali metal, alkaline earth metal or ammonium salt.

If O,O-diethyl-phosphoric acid ester chloride and 2-hydroxy-pyrazolo[1,5-a]pyrimidine are used as starting substances, the course of the reaction according to the invention can be represented by the following equation:

The (thiono)-phosphoric-(phosphonic or phosphinic)-acid ester halides or ester-amide halides of the formula (II) are known and are accessible in accordance with customary procedure. The 2-hydroxy-pyrazolo[1,5-a]pyrimidine derivatives of the formula (III) have hitherto not been described but can be prepared in accordance with methods which are in principle known. Thus, for example, the unsubstituted 2-hydroxy-pyrazolo[1,5-a]pyrimidine is obtained from a solution of 3-aminopyrazolone-(5) in ethanol and water, which has been saturated with HCl gas at 0° C., by reaction with 1,1,3,3-tetramethoxypropane. The products halogenated in the 3-position are obtained therefrom by halogenation.

The process of the invention is preferably carried out with the use of a solvent which term includes a mere diluent. As such it is possible to use practically all inert organic solvents. They include, above all, aliphatic and aromatic, optionally chlorinated hydrocarbons, such as benzene, toluene, xylene, benzine, methylene chloride, chloroform, carbon tetrachloride, chlorobenzene; ethers, for example diethyl ether, dibutyl ether, dioxane; ketones, for example acetone, methyl ethyl ketone, methyl isopropyl ketone, methyl isobutyl ketone; nitriles, for example acetonitrile, propionitrile; and formamides, especially dimethyl-formamide.

As acid acceptors it is possible to use all customary acid binders. Alkali carbonates and alcoholates, such as sodium carbonate or potassium carbonate, sodium methylate or potassium methylate or sodium ethylate or potassium ethylate, as well as aliphatic, aromatic or heterocyclic amines, for example triethylamine, dimethylamine, dimethylaniline, dimethylbenzylamine and pyridine, have proved particularly suitable.

The reaction temperature can be varied over a wide range. In general, the reaction is carried out at from about 0 to 100° C., preferably about 15 to 35° C. The reaction is generally carried out at normal pressure.

For carrying out the process, the starting substances are in most cases employed in equimolar ratios. An excess of one or other reactant does not produce any significant advantages. The reaction is preferably carried out in the presence of one of the above-mentioned solvents and in the presence of an acid acceptor, at the temperatures indicated; after stirring for one or more hours at the indicated temperatures, the reaction mixture may be worked-up by treating it with ice water. Thereupon, either the product already precipitates in solid form and is filtered off, washed and recrystallized if necessary, or the mixture is extracted with an organic solvent, preferably methylene chloride. After washing and drying the extract, the solvent is removed under reduced pressure and the oily residue is heated until slight distillation occurs.

The substances according to the invention are mostly obtained in a crystalline form and are characterized by their melting points. However, if they are obtained in the form of mostly yellowish-reddish oils, which cannot be distilled without decomposition, these may be freed of the remaining volatile constituents by so-called "slight distillation," that is to say prolonged heating under reduced pressure to moderately elevated temperatures, and may be purified in this way. In this case, their refractive indexes may be used to characterize them.

As has already been mentioned, the new O-pyrazolo-pyrimidine - (thiono) - phosphoric - (phosphonic or phosphinic)-acid esters or ester-amides are distinguished by an excellent insecticidal and acaricidal activity against crop pests, hygiene pests and pests of stored products. They possess a good action against both sucking and biting insects and mites (*Acarina*). At the same time they display only a slight phytotoxicity; they also display some rodenticidal action.

For these reasons, the products according to the invention may be successfully employed as pesticides in the protection of crops and stored products, and in the hygiene field.

To the sucking insects contemplated herein there belong, in the main, aphids (*Aphidae*) such as the green peach aphid (*Myzus persicae*), the bean aphid (*Doralis fabae*), the bird cherry aphid (*Rhopalosiphum padi*), the pea aphid (*Macrosiphum pisi*) and the potato aphid (*Macrosiphum solanifoliae*), the currant gall aphid (*Cryptomyzus korschelti*), the rosy apple aphid (*Sappaphis mali*), the mealy plum aphid (*Hyalopterus arundinis*) and the cherry blackfly (*Myzus cerasi*); in addition, scales and mealybugs (*Coccina*), for example the oleander scale (*Aspidiotus hederae*) and the soft scale (*Lecanium hesperidum*) as well as the grape mealybug (*Pseudococcus maritimus*); thrips (*Thysanoptera*), such as *Hercinothrips femoralis*, and bugs, for example the beet bug (*Piesma quadrata*), the red cotton bug (*Dysdercus intermedius*), the bed bug (*Cimex lectularius*), the assassin bug (*Rhodnius prolixus*) and Chagas' bug (*Triatoma infestans*) and, further, cicadas, such as *Euscelis bilobatus* and *Nephrotettix bipunctatus*; and the like.

In the case of the biting insects contemplated herein, above all there should be mentioned butterfly caterpillars (*Lepidoptera*) such as the diamond-back moth (*Plutella maculipennis*), the gypsy moth (*Lymantria dispar*), the brown-tail moth (*Euproctis chrysorrhoea*) and tent caterpillar (*Malacosoma neustria*); further, the cabbage moth (*Mamestra brassicae*) and the cutworm (*Agrotis segetum*), the large white butterfly (*Pieris brassicae*), the small winter moth (*Cheimatobia brumata*), the green oak tortrix moth (*Tortrix viridana*), the fall armyworm (*Laphygma frugiperda*) and cotton worm (*Prodenia litura*), the ermine moth (*Hyponomeuta padella*), the Mediterranean flour moth (*Ephesia kühniella*) and greater wax moth (*Galleria mellonella*); and the like.

Also to be classed with the biting insects contemplated herein are beetles (*Coleoptera*), for example the granary weevil (*Sitophilus granarius*=*Calandra granaria*), the Colorado beetle (*Leptinotarsa decemlineata*), the dock beetle (*Gastrophysa viridula*), the mustard beetle (*Phaeodon cochleariae*), the blossom beetle (*Meligethes aeneus*), the raspberry beetle (*Byturus tomentosus*), the bean weevil (*Bruchidius*=*Acanthoscelides obtectus*), the leather beetle (*Dermestes frischii*), the khapra beetle (*Trogoderma granarium*), the flour beetle (*Tribolium castaneum*), the northern corn billbug (*Calandra* or *Sitophilus zeamais*), the drugstore beetle (*Stegobium paniceum*), the yellow mealworm (*Tenebrio molitor*) and the saw-toothed grain beetle (*Oryzaephilus surinamensis*), and also species living in the soil, for example wireworms (*Agriotes spec.*) and larvae of the cockchafer (*Melolontha melolontha*); cockroaches, such as the German cockroach (*Blattella germanica*), American cockroach (*Periplaneta americana*), Madeira cockroach (*Leucophaea* or *Rhypharobia maderae*), oriental cockroach (*Blatta orientalis*), the giant cockroach (*Blaberus giganteus*) and the black giant cockroach (*Blaberus fuscus*) as well as *Henschoutedenia flexivitta*; further, *Orthoptera*, for example the house cricket (*Acheta domesticus*); termites such as the eastern subterranean termite (*Reticulitermes flavipes*) and *Hymenoptera* such as ants, for example the garden ant (*Lasius niger*); and the like.

The *Diptera* contemplated herein comprise essentially the flies, such as the vinegar fly (*Drosophila melanogaster*), the Mediterranean fruit fly (*Ceratitis capitata*), the house fly (*Musca domestica*), the little house fly (*Fannia canicularis*), the black blow fly (*Phormia regina*) and bluebottle fly (*Calliphora erythrocephala*) as well as the stable fly (*Stomoxys calcitrans*); further, gnats, for example mosquitoes such as the yellow fever mosquito (*Aedes aegypti*), the northern house mosquito (*Culex pipiens*) and the malaria mosquito (*Anopheles stephensi*); and the like.

With the mites (*Acari*) contemplated herein there are classed, in particular, the spider mites (*Tetranychidae*) such as the two-spotted spider mite (*Tetranychus telarius* =*Tetranychus althaeae* or *Tetranychus urticae*) and the European red mite (*Paratetranychus pilosus*=*Panonychus ulmi*), gall mites, for example the black current gall mite (*Eriophyes ribis*) and tarsonemids, for example the broad mite (*Hemitarsonemus latus*) and the cyclamen mite (*Tarsonemus pallidus*); finally, ticks, such as the relapsing fever tick (*Ornithodoros moubata*); and the like.

When applied against hygiene pests and pests of stored products, particularly flies and mosquitoes, the compounds of the invention are also distinguished by an outstanding residual activity on wood and clay, as well as a good stability to alkali on limed substrates.

The active compounds according to the instant invention can be utilized, if desired, in the form of the usual formulations or compositions with conventional inert (i.e. plant compatible or herbicidally inert) pesticide diluents or extenders, i.e. diluents, carriers, or extenders of the type usable in conventional pesticide formulations or compositions, e.g. conventional pesticide dispersible carrier vehicles such as gases, solutions, emulsions, suspensions, emulsifiable concentrates, spray powders, pastes, soluble powders, dusting agents, granules, etc. These are prepared in known manner, for instance by extending the active compounds with conventional pesticide dispersible liquid diluent carriers and/or dispersible solid carriers optionally with the use of carrier vehicle assistants, e.g. conventional pesticide surface-active agents, including emulsifying agents and/or dispersing agents, whereby, for example, in the case where water is used as diluent, organic solvents may be added as auxiliary solvents. The following may be chiefly considered for use as conventional carrier vehicles for this purpose: aerosol propellants which are gaseous at normal temperatures and pressures, such as Freon; inert dispersible liquid diluent

carriers, including inert organic solvents, such as aromatic hydrocarbons (e.g. benzene, toluene, xylene, alkyl naphthalenes, etc.), halogenated, especially chlorinated, aromatic hydrocarbons (e.g. chlorobenzenes, etc.), cycloalkanes (e.g. cyclohexane, etc.), paraffins (e.g. petroleum or mineral oil fractions), chlorinated aliphatic hydrocarbons (e.g. methylene chloride, chloroethylenes, etc.), alcohols (e.g. methanol, ethanol, propanol, butanol, glycol, etc.) as well as ethers and esters thereof (e.g. glycol monomethyl ether, etc.), amines (e.g. ethanolamine, etc.), amides (e.g. dimethyl formamide, etc.), sulfoxides (e.g. dimethyl sulfoxide, etc.), acetonitrile, ketones (e.g. acetone, methyl ethyl ketone, methyl isobutyl ketone, cyclohexanone, etc.), and/or water; as well as inert dispersible finely divided solid carriers, such as ground natural minerals (e.g. kaolins, clays, alumina, silica, chalk, i.e. calcium carbonate, talc, attapulgite, montmorillonite, kieselguhr, etc.) and ground synthetic minerals (e.g. highly dispersed silicic acid, silicates, e.g. alkali silicates, etc.); whereas the following may be chiefly considered for use as conventional carrier vehicle assistants, e.g. surface-active agents, for this purpose: emulsifying agents, such as non-ionic and/or anionic emulsifying agents (e.g. polyethylene oxide esters of fatty acids, polyethylene oxide ethers of fatty alcohols, alkyl sulfates, alkyl sulfonates, aryl sulfonates, etc., and especially alkyl arylpolyglycol ethers, magnesium stearate, sodium oleate, etc.); and/or dispersing agents, such as lignin, sulfite waste liquors, methyl cellulose, etc.

Such active compounds may be employed alone or in the form of mixtures with one another and/or with such solid and/or liquid dispersible carrier vehicles and/or with other known compatible active agents, especially plant protection agents, such as other insecticides, acaricides, and rodenticides or fungicides, bactericides, nematocides, herbicides, fertilizers, growth-regulating agents, etc., if desired, or in the form of particular dosage preparations for specific application made therefrom, such as solutions, emulsions, suspensions, powders, pastes, and granules which are thus ready for use.

As concerns commercially marketed preparations, these generally contemplate carrier composition mixtures in which the active compound is present in an amount substantially between about 0.1-95% by weight, and preferably 0.5-90% by weight, of the mixture, whereas carrier composition mixtures suitable for direct application or field application generally contemplate those in which the active compound is present in an amount substantially between about 0.0001-10%, preferably 0.01-1%, by weight of the mixture. Thus, the present invention contemplates over-all compositions which comprises mixtures of a conventional dispersible carrier vehicle such as (1) a dispersible inert finely divided carrier solid, and/or (2) a dispersible carrier liquid such as an inert organic solvent and/or water preferably including a surface-active effective amount of a carrier vehicle assistant, e.g. a surface-active agent, such as an emulsifying agent and/or a dispersing agent, and an amount of the active compound which is effective for the purpose in question and which is generally between about 0.0001-95%, and preferably 0.01-95%, by weight of the mixture.

The active compounds can also be used in accordance with the well known ultra-low-volume process with good success, i.e. by applying such compound if normally a liquid, or by applying a liquid composition containing the same, via very effective atomizing equipment, in finely divided form, e.g. average particle diameter of from 50-100 microns, or even less, i.e. mist form, for example by airplane crop spraying techniques. Only up to at most about a few liter/hectare are needed, and often amounts only up to about 15 to 1000 g./hectare, preferably 40 to 600 g./hectare, are sufficient. In this process it is possible to use highly concentrated liquid compositions with said liquid carrier vehicles containing from about 20 to about 95% by weight of the active compound or even the 100%

active substance alone, e.g. about 20-100% by weight of the active compound.

Furthermore, the present invention contemplates methods of selectively killing, combating or controlling pests, e.g. insects, acarids and rodents, and more particularly methods of combating at least one of insects and acarids, which comprises applying to at least one of correspondingly (a) such insects, (b) such acarids, (c) such rodents, and (d) the corresponding habitat thereof, i.e. the locus to be protected, a correspondingly combative or toxic amount, i.e. an insecticidally, acaricidally or rodenticidally effective amount of the particular active compound of the invention alone or together with a carrier vehicle as noted above. The instant formulations or compositions are applied in the usual manner, for instance by spraying, atomizing, vaporizing, scattering, dusting, watering, squirting, sprinkling, pouring, fumigating, and the like.

It will be realized, of course, that the concentration of the particular active compound utilized in admixture with the carrier vehicle will depend upon the intended application. Therefore, in special cases it is possible to go above or below the aforementioned concentration ranges.

The synthesis, unexpected superiority and outstanding activity of the particular new compounds of the present invention are illustrated, without limitation, by the following examples:

EXAMPLE 1

(a)

A mixture of 99.0 g. (1 mole) of 3-aminopyrazolone, 750 ml. of ethanol and 100 ml. of concentrated hydrochloric acid is saturated with gaseous hydrogen chloride at 0° C. Thereafter, 164.2 g. (1 mole) of 1,1,3,3-tetramethoxypropane are added dropwise to the mixture at an internal temperature of -5 to 0° C. and the mixture is stirred for one hour without a cooling bath and for a further hour at 50° C.

The resulting yellow salt is filtered off on a frit at 20° C. and is rinsed with ethanol and then dissolved in 1.2.1. of water, and the solution is adjusted to a pH-value of 3-4 by adding sodium hydroxide solution. The product which has precipitated is filtered off, repeatedly rinsed with water and dried. In this way, 101.0 g. (74.2% of theory) of 2-hydroxy-pyrazolo[1,5-a]pyrimidine are obtained in the form of a pale reddish powder of melting point 176 to 177° C.

(b)

47.0 g. (0.25 mole) of O,O-diethylthionophosphoric acid ester chloride are added dropwise while stirring to a mixture of 33.8 g. (0.25 mole) of 2-hydroxy-pyrazolo[1,5-a]pyrimidine, 200 ml. of dimethylformamide and 35 g. of potassium carbonate, at an internal temperature of 30° C.; the reaction mixture is subsequently stirred for a further 2 hours at 30° C. and is then treated with 330 ml. of ice-cold water at below 10° C., and the batch is twice extracted with 150 ml. of methylene chloride at a time. The combined extract is extracted by shaking three times with 200 ml. of water and the methylene chloride solution is dried over sodium sulfate. After removal of the solvent under reduced pressure and "slight distillation" of the residue, 54.9 g. (76.5% of theory) of O,O-diethyl-O-(pyrazolo[1,5-a]pyrimidin(2)yl)-thionophosphoric acid ester are obtained as a yellowish-reddish oil of refractive index $n_D^{22.5}=1.5569$.

EXAMPLE 2

(a)

135.2 g. (1 mole) of 2-hydroxy-pyrazolo[1,5-a]pyrimidine are dissolved in 1 l. of 1 N sodium hydroxide solution. 160 g. of bromine are added dropwise to this solution at an internal temperature of 40 to 50° C. while stirring, the mixture is subsequently stirred for a further hour at 50° C. and cooled to 20° C., and the reaction product is filtered off and repeatedly washed with water. The product is then suspended in ethanol, again filtered off and washed with ethanol. After drying, 186 g. (87% of theory) of 2-hydroxy-3-bromo-pyrazolo[1,5-a]pyrimidine are obtained in the form of a yellowish powder which does not have a definite melting point but gradually chars above 200° C., with decomposition.

(b)

43.0 g. (0.25 mole) of O-ethyl-ethanethionophosphonic acid ester chloride are added dropwise while stirring to a mixture of 53.5 g. (0.25 mole) of 2-hydroxy-3-bromo-pyrazolo[1,5-a]pyrimidine, 200 ml. of dimethylformamide and 35 g. of potassium carbonate, at an internal temperature of 30° C.; the reaction mixture is stirred for a further 2 hours at 30° C., and 400 ml. of ice-cold water are then gradually added at below 10° C. Hereupon, the reaction product precipitates in a crystalline form and is filtered off, repeatedly washed with water, covered with ligroin and dried. In this way, 72.1 g. (82.4% of theory) of yellowish crystals of melting point 63 to 64° C. are obtained. Recrystallization of these from 72 ml. of methanol yields 59.0 g. of O-ethyl-O-[3-bromo-pyrazolo[1,5-a]pyrimidin(2)yl]-ethanethionophosphonic acid ester, analytically pure, in the form of pale yellowish crystals of melting point 64-65° C.

EXAMPLE 3

43.0 g. (0.25 mole) of O,O-diethylphosphoric acid ester chloride are added dropwise at room temperature to a mixture of 33.8 g. (0.25 mole) of 2-hydroxypyrazolo[1,5-a]pyrimidine, 150 ml. of dimethylformamide and 27.5 g. of triethylamine, while cooling externally and stirring; the reaction mixture is allowed to continue reacting for 2 hours at room temperature, 350 ml. of ice-cold water are subsequently slowly added at below 10° C., and the batch is extracted by shaking with 200 ml. of methylene chloride. The organic phase is shaken with 100 ml. of water, dried and freed of the solvent under reduced pressure, and the residue is subjected to "slight distillation." In this way, 62.0 g. (91.5% of theory) of O,O-diethyl-O-(pyrazolo[1,5-a]pyrimidin(2)yl)-phosphoric acid ester are obtained as a yellowish-reddish oil of refractive index $n_D^{23}=1.5147$.

EXAMPLE 4

A solution of 135.2 g. (1 mole) of 2-hydroxy-pyrazolo[1,5-a]pyrimidine and 40 g. (1 mole) of sodium hydroxide in 800 ml. of water is added to a solution of 282 g. (1 mole) of Chloroamine T in 2 l. of water at an internal temperature of 5 to 15° C., while stirring and cooling

externally. After the mixture has been stirred for 1 hour at 15 to 20° C., it is treated with 60 g. of glacial acetic acid and after a further hour it is brought to a pH-value of exactly 9 and the p-toluenesulfonamide formed is filtered off and rinsed with water. 150 ml. of glacial acetic acid are added to the filtrate. After stirring for 30 minutes, the reaction product is filtered off, thoroughly washed with water, suspended in ethanol, again filtered off and rinsed with ethanol. After drying, 147.8 g. (87% of theory) of 2-hydroxy-3-chloropyrazolo[1,5-a]pyrimidine are obtained in the form of a reddish powder which does not have a definite melting point but gradually chars above 200° C., with decomposition.

(b)

(4)

36.2 g. (0.25 mole) of O,O-dimethylphosphoric acid ester chloride are added dropwise to a mixture of 42.4 g. (0.25 mole) of 2-hydroxy-3-chloropyrazolo[1,5-a]pyrimidine, 200 ml. of dimethylformamide and 26.5 g. triethylamine while stirring and cooling, at an internal temperature of 20 to 25° C.; the reaction mixture is allowed to continue reacting for 1 hour at 25° C. and 400 ml. of ice-cold water are then slowly added at below 10° C., whereupon the reaction product crystallizes out. It is filtered off, repeatedly rinsed with water, covered with ligroin and dried. In this way 49.3 g. of O,O-dimethyl-0-(3-chloropyrazolo[1,5-a]pyrimidin(2)yl)-phosphoric acid ester are obtained in the form of yellowish crystals of melting point 113 to 114° C. The product can be rendered analytically pure by recrystallization from methanol (melting point 114 to 115° C.).

EXAMPLE 5

The following compounds can be manufactured by methods analogous to those of Examples 1 to 4:

EXAMPLE 6

Plutella test

Solvent: 3 parts by weight acetone

Emulsifier: 1 part by weight alkylaryl polyglycol ether.

To produce a suitable preparation of active compound, 1 part by weight of the active compound is mixed with the stated amount of solvent containing the stated amount of emulsifier and the concentrate is diluted with water to the desired concentration.

Cabbage leaves (*Brassica oleracea*) are sprayed with the preparation of the active compound until dew moist and are then infested with caterpillars of the diamond-back moth (*Plutella maculipennis*).

After the specified periods of time, the degree of destruction is determined as a percentage: 100% means that all the caterpillars are killed whereas 0% means that none of the caterpillars are killed.

The active compounds, the concentrations of the active compounds, the evaluation times and the results can be seen from Table 2:

TABLE 2
[Plutella test]

	Active compound	Concentration of active compound in percent	Degree of destruction in percent after 3 days
(D)----		0.01 0.001	100 20
(E)----		0.01 0.001	100 0

(known)

TABLE 2—Continued

	Active compound	Concentration of active compound in percent	Degree of destruction in percent after 3 days
(16)----		0.01 0.001	100 100
(6)----		0.01 0.001 0.0001	100 100 70

13
TABLE 2—Continued

Active compound	Concentration of active compound in percent	Degree of destruction in percent after 3 days
(25)	0.01 0.001 0.0001	100 100 100
(2)	0.01 0.001 0.0001	100 100 70
(20)	0.01 0.001	100 100
(21)	0.01 0.001	100 100

EXAMPLE 7

Myzus test (contact action)/normally sensitive

Solvent: 3 parts by weight acetone

Emulsifier: 1 part by weight alkylarylpolyglycol ether.

To produce a suitable preparation of active compound, 1 part by weight of the active compound is mixed with the stated amount of solvent containing the stated amount of emulsifier and the concentrate is diluted with water to the desired concentration.

Cabbage plants (*Brassica oleracea*) which have been heavily infested with peach aphids (*Myzus persicae*) are sprayed with the preparation of the active compound until dripping wet.

After the specified periods of time, the degree of destruction is determined as a percentage: 100% means that all the aphids are killed whereas 0% means that none of the aphids are killed.

The active compounds, the concentrations of the active compounds, the evaluation times and the results can be seen from the following Table 3:

TABLE 3
[Myzus Test/normally sensitive]

Active compound	Concentration of active compound in percent	Degree of destruction in percent after 1 day
(A)	0.1 0.01 0.001	100 90 0
(F)	0.1 0.01 0.001	98 40 0

(20)	0.1 0.001	100 98
(21)	0.1 0.001	100 98
(26)	0.1 0.001	100 99 75

EXAMPLE 8

Tetranychus test/resistant

Solvent: 3 parts by weight acetone

Emulsifier: 1 part by weight alkylaryl polyglycol ether.

To produce a suitable preparation of active compound, 1 part by weight of the active compound is mixed with the stated amount of solvent containing the stated amount of emulsifier and the concentrate so obtained is diluted with water to the desired concentration.

Bean plants (*Phaseolus vulgaris*), which have a height of approximately 10–30 cm., are sprayed with the preparation of the active compound until dripping wet. These bean plants are heavily infested with spider mites (*Tetranychus urticae*) in all stages of development.

After the specified periods of time, the effectiveness of the preparation of active compound is determined by counting the dead mites. The degree of destruction thus obtained is expressed as a percentage: 100% means that all the spider mites are killed whereas 0% means that none of the spider mites are killed.

The active compounds, the concentrations of the active compounds, the evaluation times and the results can be seen from the following Table 4:

TABLE 4
[Tetranychus test/resistant]

Active compound	Concen- tration of active compound in percent	Degree of de- struction in per- cent after 2 days
(D)	0.1 0.001	0 55
(E)	0.1 0.001	0 60
(F)	0.1 0.001	0 70

50

EXAMPLE 9

55

Myzus test (contact action/resistant)

Solvent: 3 parts by weight acetone

Emulsifier: 1 part by weight alkylarylpolyglycol ether.

To produce a suitable preparation of active compound, 1 part by weight of the active compound is mixed with the stated amount of solvent containing the stated amount of emulsifier and the concentrate is diluted with water to the desired concentration.

Cabbage plants (*Brassica oleracea*) which have been heavily infested with peach aphids (*Myzus persicae*) are sprayed with the preparation of the active compound until dripping wet.

After the specified periods of time, the degree of destruction is determined as a percentage: 100% means that all the aphids are killed whereas 0% means that none of the aphids are killed.

EXAMPLE 10

Phorodon test (contact action/resistant)

60 Solvent: 3 parts by weight acetone

Emulsifier: 1 part by weight alkylarylpolyglycol ether.

To produce a suitable preparation of active compound, 1 part by weight of the active compound is mixed with the stated amount of solvent containing the stated amount of emulsifier, and the concentrate is diluted with water to the desired concentration.

Hop plants (*Humulus lupulus*) which have been heavily infested with the hop aphid (*Phorodon humuli*) resistant, are sprayed with the preparation of the active compound until dripping wet.

After the specified periods of time, the degree of destruction is determined as a percentage: 100% means that all the aphids were killed; 0% means that none of the aphids were killed.

75

The active compounds, the concentrations of the active compounds, the evaluation times and the results can be seen from the following Table 6:

TABLE 6
[Phorodon humuli test/resistant]

Active compound	Concentration of active compound in percent	Degree of destruction in percent after 1 day
(G)----- 	0.1 0.02 0.004	75 70 40
(known)----- 	0.1 0.02 0.004 0.0008	100 100 90 20
(9)----- 	0.1 0.02 0.004 0.0008	100 100 100 85
(10)----- 	0.1 0.02 0.004 0.0008	100 100 100 75
(2)----- 	0.1 0.02 0.004 0.0008	100 100 100 40

It will be appreciated that the instant specification and examples are set forth by way of illustration and not limitation, and that various modifications and changes may be made without departing from the spirit and scope of the present invention.

What is claimed is:

1. An O-pyrazolopyrimidine - (thiono) - phosphoric-
(phosphonic or phosphinic)-acid ester of the formula

in which

R_1 is alkoxy or alkyl with 1 to 6 carbon atoms,
 R_2 is alkyl or alkoxy with 1 to 6 carbon atoms or phenyl or monoalkylamino or dialkylamino with up to 6 carbon atoms in each alkyl moiety,
 R_3 is hydrogen or halogen, and
 X is oxygen or sulfur.

2. A compound according to claim 1 in which R_1 is lower alkyl or alkoxy, R_2 is lower alkyl or alkoxy, phenyl, mono-lower alkylamino or di-lower alkylamino, and R_3 is hydrogen, chlorine or bromine. 70

3. The compound according to claim 1 wherein such compound is O - ethyl - O - [3-bromo-pyrazolo[1,5-a]pyrimidin(2)yl]-ethanethionophosphonic acid ester of the formula

10 4. The compound according to claim 1 wherein such compound is O,O - diethyl - O-[3-chloro-pyrazolo[1,5-a]pyrimidin(2)yl]-thionophosphoric acid ester of the formula

5. The compound according to claim 1 wherein such compound is O - ethyl - O - (pyrazolo[1,5-a]pyrimidin (2)yl)-ethanethionophosphonic acid ester of the formula

6. The compound according to claim 1 wherein such compound is O - ethyl - O - [3 - chloro-pyrazolo[1,5-a]30 pyrimidin(2)yl]-ethanethionophosphonic acid ester of the formula

7. The compound according to claim 1 wherein such compound is O-isopropyl - O - [3-chloro-pyrazolo[1,5-a]pyrimidin(2)yl]-methanethionophosphonic acid ester of the formula

8. The compound according to claim 1 wherein such compound is O - isopropyl - O-[3-bromo-pyrazolo[1,5-a]pyrimidin(2)yl]-methanethionophosphonic acid ester of 50 the formula

9. The compound according to claim 1' wherein such compound is O,O - diethyl - O-[3-bromo-pyrazolo[1,5-a]pyrimidin(2)yl]-phosphoric acid ester of the formula
